UNITED STATES PATENT OFFICE.

WILLIAM E. CRIST, OF BALTIMORE, MARYLAND, ASSIGNOR OF ONE-HALF TO GEORGE E. CRIST, OF SPARROWS POINT, MARYLAND.

JOURNAL-BOX.

1,083,905.

Specification of Letters Patent.

Patented Jan. 6, 1914.

Application filed December 9, 1911. Serial No. 664,769.

To all whom it may concern:

Be it known that I, WILLIAM E. CRIST, a citizen of the United States, residing in the city of Baltimore and State of Maryland, have invented a new and useful Improvement in Journal-Boxes, of which the following is a specification.

This invention relates to improvements in journal boxes and more particularly to those used on railway locomotive tenders, passenger, freight and other car boxes which have the journal boxes located on the axles outside of the wheels. It will be understood, however, that the invention may be applied to other forms of journal boxes without departing from the spirit of the invention.

The improvements consist essentially in providing means for ventilating the interior of the journal boxes so that the stale air within the journal box, external to the journal and bearing and alongside of same, is caused to be drawn or forced out of the box and replaced by fresh atmospheric air, this change being caused by nozzles either of the direct or the induced draft type and so located that they will act upon the air space inside the journal box directly alongside of the journal and its bearing.

My invention consists more specifically in providing an air inlet and an air outlet communicating with the space inside of the journal box directly around and about and alongside the outside of the journal bearing. These inlet and outlet orifices may be combined in a single hole or orifice, or there may be two such orifices, one in the forward and one in the rear side of the main portion of the journal box or two sets of such inlet and outlet holes arranged as desired on the journal box.

Furthermore, my improvements may consist in a structure wherein the cool or outside air passes directly into the journal box from the front or advance side of the journal box as the train is moving, and which will thus force the heated air within the journal box out at the rear side, and the cool air thus replace the heated air. The ingress and egress of the air may be made through orifices directly in line with each other or the air may be made to follow a more tortuous course. On the other hand, the inlet and outlet orifices may be so constructed that the cool air is drawn into the journal box from the rear side of the mov-

ing journal box, and the heated air drawn out at the front side, and in this latter case, the use of a partial vacuum is employed, as will be better understood from the following description.

By the structure which I employ, a continuous change of air is produced within the journal box directly around and about the sides of the journal and bearing without liability of sand, dust or any other undesirable foreign substances being introduced therein, and it also provides a journal box that is practically non-heating, and thus prevents the delays in operating trains caused by heated car journals, and thereby materially reduces the cost of maintenance of the same. It will also be obvious that my improvements may be applied not only to new car journal boxes, but that they may also be readily applied on journal boxes already in use.

My invention furthermore consists in the novel improvements in the parts and devices and in the novel combinations of parts and devices herein shown, described and claimed.

In the drawing, wherein is illustrated one form of my invention, and the one which I now consider preferable, Figure 1 is a side view of a journal box showing my improvements. Fig. 2 is a vertical section of the improved journal box, taken on the line 2-2 of Fig. 1, and looking in the direction of the arrows, Fig. 3 is an enlarged detail, sectional view taken on the line 3-3 of Fig. 2, looking in the direction of the arrows.

In the drawings, 10 represents the main portion of the journal box, which is provided with the usual lugs 11 and 12 on the sides thereof, by means of which the journal box is adapted to be bolted to the car truck. On each side of the main portion 10 of the journal box is a shell or outside member 13, forming with the inner portion 14, a vertically extending recess 14^a, as more clearly shown in Fig. 2, and having an opening 15 at the bottom thereof and also an opening 16 at the top. The inner portion 14 of the main member of the journal box is provided also on each side with a hole or orifice 17, which is located substantially opposite the hole or orifice 16 in the outer shell member 13, as shown in the drawings which are merely illustrative. Located between each of the outer portions 13 and the inner member 14 and preferably cast integrally

therewith, is a web or plane 18, each of said plates 18 extending beyond the lower portions of the holes or recesses 16 and 17.

Preferably located in each of the orifices

- 5 17 is a screen 19, removably secured therein as by means of a resilient coil member 20 adapted to be seated in a groove 21 in the inner portion 14 of the journal box, said screen 19 abutting a ledge 22 in the member 14.

10 It will be apparent that if the journal box is mounted on a train going in the direction indicated by the arrow *a* in Fig. 2, that the atmospheric pressure will be increased on 15 the forward or advance side of the journal box, and that a current of air will flow in the direction, as indicated by the small arrows *b*. Such a flow of air will produce a 20 partial vacuum between the web 18 and the inner portion 14, thereby drawing the 25 heated air from the interior of the journal box through the orifice 17, which will then mix with the flow of air being forced through the hole 16 and which will then 30 pass out at the hole 15. In this way, a partial vacuum is created in the interior of the journal box, which in turn induces an inflow of air through the orifice 17 on the rear side of the journal box. It will be ob- 35 vious when the train goes in the opposite direction, that the flow of air through the journal box will be in the reverse direction, or in other words, that upon the train going in one direction, one hole or orifice serves as the inlet hole and the other for the outlet hole, and that upon going in another direction, the function of the holes is reversed.

Any suitable form of cover or lid 24 may be used with the journal box.

- 40 It will be obvious that many changes may be made in the details of my invention without departing from the spirit thereof, and

all such changes are contemplated as fairly come within the scope of the appended claims.

I claim—

1. As an article of manufacture, a journal box adapted for use on railway cars provided with an air passageway on the exterior of the box and through which a draft 50 of air is produced when the car is in motion, said journal box being provided also with another passageway communicating with the interior of the box and with the first named passageway, whereby the air from 55 the interior of the box is withdrawn by suction induced by said air draft when the car is in motion.

2. As an article of manufacture, a journal box adapted for use on railway cars, and 60 provided with a pair of oppositely arranged air passageways on the exterior of the box through each of which a draft of air is adapted to be produced when the car is in motion, said journal box being provided also 65 with another pair of passageways each communicating with the interior of the box and with one of the first named passageways, whereby the air from the interior of the box is withdrawn by suction induced by the air 70 draft through either of the first named passageways when the car is in motion.

3. As an article of manufacture, a journal box adapted for use on railway cars and provided with means for withdrawing air 75 from the interior of the journal box by suction induced by the velocity of the atmospheric air draft passing over an air passageway leading from the interior of the box, substantially as specified.

WILLIAM E. CRIST.
